CLOTH MARKING MACHINE

Edward F. Smith, Cincinnati, Ohio, assignor to
 The Wolf Machine Company, Cincinnati, Ohio,
 a corporation of Ohio

Application August 8, 1946, Serial No. 689,295

4 Claims. (Cl. 101—26)

1

This invention relates to a machine for marking cloth and more particularly to a machine for marking a number of layers of cloth in a single operation.

It is common practice in the mass production of clothing to cut cloth a number of layers at a time with a cloth cutting machine. Certain places must be marked on all layers, for example, the positions of button holes, buttons, inserts, and the like, and it is most convenient to mark all the layers in a single operation before the layers are separated. However, none of the machines currently available for marking a number of layers of cloth are fully satisfactory, and it has been a principal objective of this invention to develop a marking machine suitable for marking a number of layers of cloth in a single operation to apply a clear, lasting mark which is easy to locate and which can be completely removed from the cloth when no longer needed.

Marking machines have been suggested in which a perforation is made through a number of layers of cloth. Such marking or perforating machines, however, leave a mark which rapidly disappears and for this reason is unsatisfactory. Another type of machine heretofore employed is one which inserts a thread through the layers of cloth. This type of machine is also unsatisfactory in that the thread must be cut between each pair of layers of cloth in a tedious, time-consuming operation and because the thread makes such a small mark that it is difficult to find.

Briefly stated, this invention provides a marking machine in which a pigmented mark is left on the cloth. A needle having a hollow bore is used which acts to perforate the cloth and at the same time to lead a marking liquid through the bore of the needle into various layers of cloth.

It has been found that a needle of appropriate dimensions to carry a marking fluid can be driven through layers of cloth with ease only when the needle is being rotated; and, therefore, a further objective of this invention has been to produce a marking machine having a rotating needle with a hollow bore.

As a marking fluid, a suspension of chalk or other pigment in a volatile organic fluid, for example, carbon tetrachloride, is preferably employed. This suspension rapidly penetrates cloth to leave a clear, white mark on the cloth which mark can easily be brushed away when no longer needed. However, the suspension rapidly stratifies upon standing to leave a layer of chalk particles and a layer of liquid above the chalk particles in the tank or reservoir. Therefore, a fur-

2

ther objective of this invention has been to provide means for mixing the chalk and fluid when the marking machine is in operation. This is accomplished by rotation of the liquid reservoir. Stationary baffles are provided within the reservoir which act to mix liquid and chalk within the reservoir when the machine is in use, and the liquid reservoir and the needle are rotated together.

10 In order to provide a sufficient flow of marking fluid through the bore of the needle when it is being used to mark cloth, the bore must be of sufficient diameter to permit marking fluid to flow through the needle rapidly. On the other hand, when the needle is raised from the goods, the flow of marking fluid must be cut off. Therefore, it has been a further objective of this invention to provide a marking machine in which marking fluid flows through the bore of the marking needle only while the needle is being inserted through layers of cloth and in which the flow of marking liquid is cut off as soon as the needle is raised.

25 In the embodiment disclosed marking fluid is fed into the marking needle through an opening in the upper portion of the needle. A valve and gasket arrangement is provided whereby, so long as the needle is raised above a bolt of cloth, the needle is forced downwardly with relation to the reservoir until the opening is covered by a gasket. On the other hand, when the marking machine is lowered and the needle is forced into the cloth, the pressure required to force the point of the needle into the cloth is sufficient to raise the needle with respect to the reservoir until the opening in the upper portion of the needle is above the gasket and in position to permit marking fluid to flow through the bore of the needle.

30 When a marking operation has been completed, the marking fluid remaining in the bore of the needle must be removed therefrom, for if residual fluid is left in the bore of the needle, the chalk contained in it tends to settle out in the bore of the needle to clog the bore and prevent proper flow of fluid when next the machine is set in operation. A quick and convenient method for 40 cleaning the bore of the needle at the end of a period of use of the machine is provided in the marking machine of this invention. The motor drive is stopped for a short period during which the chalk rapidly settles out of suspension into a trough which surrounds the gasket. The gasket itself is set in a slightly raised position in the liquid reservoir to give a sufficient volume of space in the reservoir below the gasket to accom-

modate all the chalk which can settle out of suspension. After the chalk has settled, the needle is raised briefly with respect to the reservoir to permit a small amount of clear fluid from above the chalk layer to flow through the bore of the needle to clean it.

Various other advantages and features of the invention will be more fully set forth in the description of the accompanying drawings, in which:

Figure 1 is a side view of a marking machine constructed in accordance with this invention, the handle for use in raising and lowering the machine being shown partly in dotted lines for clarity.

Figure 2 is a plan view of the marking machine illustrated in Figure 1.

Figure 3 is an enlarged detailed sectional view of the lower needle guide, the section being taken on line 3—3 of Figure 1.

Figure 4 is a sectional view taken on line 4—4 of Figure 3.

Figure 5 is an enlarged sectional view, taken on line 5—5 of Figure 1 showing the liquid reservoir and needle guides of the marking machine illustrated in Figure 1.

Figure 6 is an enlarged detail view of the needle showing it partly broken away and partly in section.

Figure 7 is a sectional view taken on the line 7—7 of Figure 5.

Figure 8 is a side view of the marking machine showing the machine partly lowered into marking position.

Figure 9 is a fragmentary detailed sectional view taken from Figure 5 showing the needle raised with respect to the liquid container, the needle being shown in position for liquid flow through its bore.

Figure 10 is a sectional view taken on line 10—10 of Figure 5.

As illustrated in Figures 1 and 2 the marking machine includes an L-shaped main support 10 one end of which is attached to and supported by a table 11. The support 10 carries an electric motor 12 which, by means of a belt 13, turns a marking needle 14 and a liquid reservoir 16. A handle 17 is used to lower the needle and reservoir to force the needle to drill through a stack 18 of layers of cloth or other material to be marked by the machine. A pair of upright guides 19 mounted on the support 10 guide the vertical movement of the needle and reservoir.

The stack 18 is made up of a number of layers of cloth all of which are to be marked with a single pattern. The cloth rests on the top of the table and is free to be moved across the table and under the marking needle 14.

The needle 14 is constructed of tubular material to conduct liquid from the reservoir 16 through an opening 20 near the point of the needle to mark the cloth. Between marking operations the stack 18 is moved with respect to the table 11 so that the needle 14 is above the point in the cloth at which a mark is to be made before the handle 17 is lowered.

The handle 17 includes a main lever 22 and a short lever 23 which join at a pivot 24. The lever 23 is pivotally mounted on the support 10 at a pivot point 25. The lever 22 is pivotally connected to a reservoir mounting bracket slidably engaged on the upright guide 19 and pivots thereon at a point 26. This arrangement of levers permits the marking machine to be lowered when the handle 17 is lowered and also

provides a means for holding the reservoir 16 and needle 14 in raised position, as shown in Figure 1. When the handle 17 is raised, the levers lock in raised position to hold the reservoir in raised position and support the needle above and free of the bolt of cloth. A stop 27 attached to an extension of the lever 22 binds against the lever 23 to hold the reservoir and needle in raised position and to prevent them from being raised too far.

A cloth hold-down plate or presser foot 28 is provided and is bolted to a bracket 40 mounted on an upright bar 29. The bar 29 in turn rides through an opening in a flange 30 attached to the support 10 and an opening in a support member 31 attached to the liquid reservoir 16. An adjustable member 32 is slidably mounted upon the bar 29, and a spring 33 connects the member 32 with the support 10. When the machine is to be used, the hold-down plate or presser foot 28 is raised so that the stack of cloth 18 moves freely under the hold-down plate when the handle 17 is raised. Then the member 32 is engaged against the support member 31 and is tightened upon the rod 29 by turning a clamping handle 34.

In this position, the hold-down plate 28 is pulled down against the stack of cloth 18 by the spring 33 as long as the handle 17 is lowered, as shown in Figure 8, but, when the handle is raised, as shown in Figure 1, the hold-down plate is raised above the stack 18 to permit the stack to be moved preparatory to further marking. As shown in Figure 10, one side 35 of the bar 29 is flat and fits against corresponding straight edges on the flange 30 and support member 31 to prevent rotation of the hold-down plate 28. The needle 14 is provided with a pair of movable guides 36 and 37 and, in addition, a lower guide 38 which is attached to the hold-down plate 28. Details of the lower guide and of the hold-down plate are shown in Figures 3 and 4. The lower guide 38 includes a funnel shaped guiding member 39 carried on a bracket 40 which bracket is attached to the upright bar 29 and, further, serves to connect the hold-down plate 28 to the bar 29. The funnel shaped member 39 serves to direct the point of the needle 14 into proper orientation for piercing the cloth at a proper point. The hold-down plate 28 includes a V-shaped slot beneath the guide 38 which slot 41 serves to clear the needle 14 as it passes through the stack of cloth 18 when the needle is lowered.

Referring again to Figures 1 and 2, a suitable marking liquid is fed into the needle 14 from the reservoir 16. A preferred marking liquid for use with this marking machine is one which includes a suspension of powdered chalk in a carrier of carbon-tetrachloride. However, other marking mixtures may be used with the apparatus of this invention without departing from the spirit thereof. The chalk-carbon tetrachloride mixture is advantageous because it quickly penetrates the fibers of a piece of cloth to deposit a white chalk mark in the goods. Also the carbon tetrachloride rapidly evaporates from the goods without leaving any residue. Further the chalk mark deposited can easily and quickly be brushed off the goods when the mark is no longer desired so as to leave no residue of marking material on the goods.

A chalk-carbon tetrachloride marking mixture rapidly separates into its components and stratifies on standing and must be agitated constantly while in use in order to keep the solid chalk sus-

pended in the liquid. The apparatus for agitating the marking mixture can be understood most clearly by reference to Figure 5, which shows details of the liquid reservoir. The reservoir 16 includes a glass of plastic shell 42 having a metal upper cover 43 and an inverted cone-shaped metal bottom 44. The bottom of the reservoir is configurated to provide a raised central portion 44b which is surrounded by a trough 44a. Around the hub of the bottom 44 is an integral V-type pulley 45 around which the belt 13 passes. The cover 43, the bottom 44, and the glass shell 42 are held together by means of a series of tie-bolts 46. Gaskets 47 fit between the shell 42, the cover 43 and the bottom 44 to provide a liquidtight seal.

During operation of the marking machine, the liquid reservoir, including the shell 42, the top 44 and the bottom 45, rotates. The rotating portions are mounted in ball bearings 48. The bearings in turn are mounted in an upper support member 49 and the lower support member 31, which members are slidably mounted on the guides 19 so that the reservoir 16 and also the members 31 and 49 slide vertically along the guides 19 while the liquid containing shell 42 and the covers 43 and 44 are rotated by the belt 13.

Details of the sliding mounting are shown in Figures 2, 5, and 10. Each of the support members 31 and 49 is equipped with a pair of split lugs 50 which are mounted on arms extending from the support members and which fit around the sleeves 53 on the guides 19. Each split ring 50 in turn is closed by means of a bolt 51 which can be tightened to clamp the split ring. The sleeves 53 fit about the guides 19 and act as spacers between the support members 31 and 49. As illustrated in Figure 5, a section of restricted cross-section 56 is provided at each end of each of the sleeves 53 and the sections 56 fit inside the split rings 50. Thus, when the bolts 51 are tightened to draw up the split rings 50 about the ends of the sleeves 53, a positive grip is provided between the split rings and the sleeves to hold the support members 31 and 49 in spaced assembled relation. A threaded lug 54 formed as a part of the split ring 31, serves as a center for the pivot point 26 on the lever 22.

A filling tube 55 passes through an opening in the center of the cover 43. The tube is attached by means of a set screw 52 to a support 57 attached to the member 49. A gasket 58 which surrounds the filling tube 55 prevents liquid from inside the shell 42 passing up along the outside of the tube 55 and protects the upper ballbearing 48 from marking fluid, which, except for the gasket 58, might pass from the inside of the reservoir 16 along the sides of the filling tube 55 into the ballbearing. The tube is used to introduce fluid into the reservoir 16 and carries at its lower end a collar 55a having radial flanges 55b which are fixed to paddles 59. The paddles 59 are constructed to remain stationary while the shell 42 revolves. Thus, the paddles serve to stir the liquid in the reservoir while the reservoir rotates. A series of slots 60 cut in the lower portion of the paddles 59 permits some of the fluid in the reservoir to rotate with the reservoir and thus improves the stirring action. A felt scraper 61 is attached to one of the paddles 59 and serves to scrape any material from the walls of the shell 42 which may adhere thereto.

Details of the needle construction can best be seen by reference to Figure 6. The needle is

constructed from a length of small diameter metal tubing and has a bore 62 which extends the length of the needle. At the lower end of the needle is a point 63 which is soldered into the tubing of the needle. The lower opening 20, constituting a fluid egress port, is cut from the side of the needle just above the point 63, and marking fluid flows from the needle through this opening into the cloth to be marked by the needle. An opening 65, constituting a fluid entry port, in the side of the upper portion of the needle permits liquid to enter and flow through the bore 62 of the needle.

The marking liquid is fairly free flowing and must flow through the needle only when cloth is being marked therewith. Otherwise, if marking fluid flowed continuously, it would fall on the upper layer of cloth while the needle was raised to spot the upper layer. Therefore, the needle is so mounted that liquid flows through the bore of the needle only while the needle is in contact with a stack of cloth.

Referring again to Figure 5 the needle passes through a guide bore 66 formed through the center of the bottom 44.

A needle support 67 having a pair of small keys 68 is firmly attached centrally of the support 67 and the support 67 fits inside the bore 66 and slides vertically therein. As shown in Figure 7, the support 67, is cut away at one side to permit the passage of air through the bore 66 and along the side of the support 67 as the support 67 moves up or down through the bore 66. The support 67, as illustrated in Figures 5 and 7, is keyed to, and the needle 14 rotates with, the bottom 44. Keyways 69 are cut in the inner walls of the bore 66, and the upper ends of the keyways 69 form a limit stop as shown in Figure 9, limiting upward movement of the needle and support. A lower needle stop is provided by a cap 70 which is threaded on the axial extension of the bottom 44 and through the center of which the needle passes.

The upper part of the needle passes through a gasket or packing gland 71 in the upper portion of the guide bore 66 which gasket covers the upper opening 65 of the needle, as shown in Figure 5, when marking liquid is not flowing through the needle. A valve 72 mounted on a bracket 73 above the needle 14 forces the needle 14 downwardly into the position shown in Figure 5 through the action of a spring 74 when the needle is not in operation to mark a stack of cloth. The valve bracket 73 is connected to the bottom 44 by means of a plate 75 threaded to the upper end of the internal upper extension of the bottom 44 which plate serves not only to support the valve bracket 73 but also to hold the gasket 71 in place. The gasket 71 is mounted in a counterturned portion 76 in the upper end of the guide bore 66 and the plate 75 acts to close the upper end of the bore.

A bore 77 is provided through the center of the plate 75 to guide the upper end of the needle 14. The upper portion of the plate includes a tapered valve seat 78 for the valve 72.

The valve 72 is mounted on the lower end of a valve stem 79 guided by a guide 81 which forms a part of the valve bracket 73. The guide 81 is carried by a series of rods 82 which in turn are attached to the plate 75. The valve stem 79 is guided in a bore 83 in the guide 81. The guide element 81 acts as a backing member for the spring 74 which spring acts to urge the valve 72 against the valve seat 78. When the machine is

lowered to bring the point 63 of the needle against a stack of cloth, the needle is forced upwardly with respect to the reservoir 16 to open the valve 72 (as shown in Figure 9), until the opening 65 in the side of the upper part of the needle is above the gasket 71 to permit marking liquid to enter the bore of the needle and flow down the needle into the cloth. When, on the other hand, the machine is raised the spring 14 forces the needle downward with respect to the reservoir and the valve 72 is forced against the valve seat 78 while the gasket 71 covers the upper opening in the needle to cut off the flow of liquid to the needle.

As the reservoir 16 is lowered the guides 36 and 37 approach the lower guide 38. The guides 36 and 37 are slidably mounted for vertical movement to permit relative sliding movement between the guides and the reservoir when the needle is pushed through the bolt of cloth. Details of the construction of the guides 36 and 37 are shown in Figure 5. The upper guide 37 consists of a horizontal bar 85, one end of which is mounted on the lower end of a vertical slide bar 86 while a slot 87 is formed through the other end of the bar 85 to receive the needle 14. The vertical bar 86 is square in cross-section and passes through openings 88 in flanges attached to the support members 31 and 49 and moves freely vertically through the openings 88 (see Figure 2). A pin 90 is attached to the upper part of the bar 86 and prevents the bar from falling free from the reservoir. The openings 88 are square in shape to prevent twisting of the bar 86 and are held in place by plates 91 for ease in assembling.

The guide 36 consists of a L-shaped bar 92 one end of which is attached to a second bar 93. The bar 93 in turn is equipped with flanges 94 formed by bending out the ends of the bar 93. Square openings 95 in the flanges 94 are traversed by the bar 86 and the guide 36 is free to slide vertically along the bar 86, its movement being limited to the distance the guide 36 can slide before one of the flanges 94 engages one of the support members 31 and 49. A slot 96 formed in the free end of the bar 92 is traversed by the needle. Thus the needle guides 36 and 37 are prevented from rotating and give the needle 14 support against bending.

As the needle descends the reservoir and needle move downwardly relative to the guides 36 and 37, as shown in Figure 8, allowing the needle to penetrate further into the cloth. However, when the needle is raised once more, the guides 36 and 37 fall back into place under the influence of gravity to support the needle 14 against bending.

At the lowest point in its descent the point 63 of the needle 14 passes below the level of the table 11 and, as shown in Figure 1, the table 11 is equipped with an opening 97 below the needle 14 into which the point of the needle extends at the lowest point of its descent. This cut-out portion or opening 97 is required to permit the needle to descend far enough to mark the lowest layers of cloth in the stack of cloth 18.

The operation of the marking machine has been described generally with respect to the foregoing description of the structure. The operation will be set out more fully below.

When the machine is to be operated it is filled with the marking liquid to a level 98 as shown in Figure 5. The filling tube 55 has a small air hole 99 which serves to limit the height to which the reservoir can be filled. Once the level of the liquid rises to the opening 99, air backs up above

the liquid and prevents further filling. This makes it impossible to fill the reservoir to the brim, which would be undesirable because, during rotation of the reservoir 16, liquid would rise up to the upper cover 43 if the reservoir were filled to the brim and might pass out of the reservoir to reach the upper ball bearing 48 or to slop out of the machine. A stopper 100 closes the top of the filling tube 55.

Next, a stack of layers of cloth is placed upon the table 11 and moved until the first point to be marked is below the V-notch of the presser foot 28. Then the electric motor 12 is set in operation to rotate the needle and reservoir and to mix the chalk with the carbon-tetrachloride carrier to form a marking mixture. When the marking mixture has been stirred enough to give a uniform suspension, the handle 17 is lowered to bring the point 63 of the needle 14 through the lower guide 38 until it comes in contact with the stack of cloth 18. At this point the presser foot 28 is urged into position by the spring 33 to prevent further movement of the stack of cloth 18. As the handle 17 is further lowered the needle rises with respect to the reservoir 16 until the opening 65 is above the gasket 71 and within the liquid in the reservoir. The handle 17 is further lowered to drive the needle 14 completely through the stack of cloth; and, while the needle passes through the cloth, marking fluid flows through the bore of the needle and out through the opening 20 to leave a mark on each layer of cloth in the stack 18.

When the needle 14 has passed completely through the bolt of cloth 18, the handle 17 is raised once more and the needle is pulled back up through the bolt. At this point the spring 74 acts to close the valve 72, and the needle 14 descends with relation to the reservoir while being raised through the cloth thus shutting off the flow of liquid to the needle 14. When the handle 17 is raised to its full height, the element 32 is automatically raised by the reservoir support member 31 to lift the hold-down plate 28 from the stack of cloth and permit the stack to be moved preparatory to the next marking operation.

The chalk carbon-tetrachloride mixture would act to clog the bore of the needle 14 if it were left in the bore and allowed to dry therein. Therefore, when the machine is to be left idle, the bore of the needle must first be cleaned. This is done simply. The motor 12 is stopped to permit the reservoir to stop rotating. In a short time, the chalk settles out of the marking mixture to leave a layer of clear carbon-tetrachloride above the chalk. The chalk settles into the cone-shaped trough 44a of the bottom 44 below the level of the gasket 71. Then the needle 14 is manually raised sufficiently to permit clear carbon-tetrachloride to pass through the bore of the needle to clean any remaining marking mixture out of the bore of the needle and leave the needle in condition for standing idle.

When the needle is pulled out of the layers of cloth, the port hole or opening 65 in the side of the needle at the top is then open slightly below the gasket which allows air to get in the top of the needle and completely drain the needle before it is pulled out of the cloth.

In other words, the needle must be drained, which is accomplished by preventing the formation of a vacuum at each marking operation. Since the opening in the top of the needle is a little below the gasket or guide, air can get to the

top of the needle bore and all remaining liquid in the needle is completely drained out leaving a clean needle for the following operation.

The nut that holds the needle in place has a vent hole 101 drilled in it to allow air to pass up the flat side of support 67 (Figure 7) and enter at the top of the needle.

Having described my invention, I claim:

1. In a machine for marking cloth with a marking fluid which is composed of a mixture of finely divided pigment particles and volatile liquid and which is characterized by rapid settling of the particles unless agitated, a fluid reservoir, the bottom of the reservoir configurated to provide a raised central portion and a trough surrounding said portion, a packing gland within the raised central portion, an elongated hollow needle having an entry port adjacent its upper end and an egress port adjacent its lower end, the upper end of said needle slidably mounted within said packing gland and movable between a position in which the entry port is within and closed by said packing gland and a position in which said entry port is above said packing gland and open to the reservoir, spring means urging said needle toward the first of said positions, means for rotating said reservoir, means for agitating marking fluid within the reservoir operable only upon rotation of the reservoir, means for lowering said reservoir while the reservoir is rotating to force the needle to pierce a stack of cloth, whereby the needle upon contact with the cloth is moved upwardly relative to the packing gland to open the entry port to agitated marking fluid in the reservoir and permit said fluid to flow through the hollow needle, and said needle adapted to be raised when the reservoir is still and the pigment particles settled into the trough to open the entry port to particle-free liquid, and permit said particle-free liquid to flow through the hollow needle in order to wash out deposited pigment.

2. In a machine for marking cloth with marking fluid which is composed of a mixture of finely divided pigment particles and volatile liquid and which is characterized by rapid settling of the particles unless agitated, a fluid reservoir, the bottom of the reservoir configurated to provide a raised central portion and a trough surrounding said portion, said trough adapted to receive settled pigment particles when fluid within the reservoir is unagitated, leaving the upper end of the raised central portion within particle-free liquid, a packing gland within the upper end of said raised central portion, an elongated hollow needle having an entry port adjacent its upper end and an egress port adjacent its lower end, the upper end of said needle slidably mounted within said packing gland and movable between a lower position in which the entry port is within and closed by said packing gland and an upper position in which said entry port is above said packing gland and open to the reservoir, means urging said needle toward said lower position, and means for agitating fluid within the reservoir.

3. In a machine for marking cloth with a marking fluid which is composed of a mixture of finely divided pigment particles and volatile liquid and which is characterized by rapid set-

ting of the particles unless agitated, a marking fluid reservoir, a trough disposed in the bottom of the reservoir for collecting settled pigment particles, a packing gland disposed above said trough and carried by said reservoir, an elongated hollow bore needle having the upper end thereof longitudinally movable within the packing gland, said needle having entry and egress ports communicating with the hollow bore thereof, the entry port positioned relative to the packing gland so as to be closed by said packing gland upon downward movement of the needle, resilient means urging the needle in said downward direction, means for rotating said reservoir, means for agitating marking fluid within said reservoir operable only upon rotation of the reservoir, and means for lowering said reservoir while it is being rotated to force the needle to pierce a stack of cloth whereby the needle upon contact with the cloth is moved upwardly relative to the packing gland to open the entry port to agitated marking fluid and permit said fluid to flow through the needle and mark cloth.

4. In a machine for marking cloth with a marking fluid which is composed of a mixture of finely divided pigment particles and volatile liquid and which is characterized by rapid settling of the particles unless agitated, the combination of a fluid reservoir, the bottom of the reservoir configurated to provide a raised central portion and a trough surrounding said portion, said trough adapted to receive settled pigment particles when the fluid within the reservoir is unagitated, leaving the upper end of the raised central portion within particle-free liquid, a packing gland within said raised central portion and an elongated hollow bore needle slidably mounted within said packing and depending below said reservoir, an entry port adjacent the upper end of said needle, said needle being vertically movable between a lower position in which said entry port is within and closed by said packing gland and an upper position in which said entry port is above said packing gland and open to fluid within the reservoir, means urging said needle toward said lower position, and means for agitating fluid within said reservoir.

EDWARD F. SMITH.
